UNITED STATES PATENT OFFICE

JAKOB BECK, OF BERLIN, GERMANY

FILE

Application filed April 29, 1929, Serial No. 359,133, and in Germany November 12, 1928.

File arrangements have become known, in which the newspapers, periodicals, books of music or the like are filed in covers with the aid of filing pins. These arrangements present however the inconvenience that the filing holes in the newspapers, books of music or the like, tear out easily or get wider at repeated use so that the filed papers get loose. To obviate this inconvenience it has been proposed to reinforce the paper edge or to insert in the fold of the book a wire, a strip of fabric or the like. These precautions are not only troublesome and expensive but they do not prevent the books from getting loose as they cannot be maintained in the files.

It has further been proposed to provide on the inner surface of the back of the file at the filing points clamping springs on the one hand designed to securely hold the filed newspapers or books and on the other hand carrying pins engaging with the perforations of the filed newspapers, book or sheets. These pins are hingedly connected to the clamping springs and telescoped the one into the other, a special key being required for opening the filing pins. This inconvenience is due to the fact that the ends of the clamping springs are not accessible but hidden in the file back and situated underneath the edges of the cover back so that these files are not easy to manipulate and rather expensive.

All the above mentioned inconveniences are obviated by the present invention, according to which holding means for the filing pins are arranged on the back of the file at the leaf-impaling points, said holding means projecting over the edges of the cover and being controlled by resilient or elastic elements so that they strongly press together the filed sheets or hooks at the filing points.

These means for holding the filing pins may be of various constructions; they may consist of the ends of clamping springs inserted in the back of the file, or they may be bent outward from a continuous bar arranged in the back of the file.

The holding means for the filing pins may be hook-shaped, eye-shaped, consist of claws, or be made in any other suitable form.

As filing pins narrow or flat metal strips, preferably of spring steel, are used.

Several embodiments of the invention are illustrated by way of example in the accompanying drawings in which:—

55

Fig. 1 shows an open file in front elevation.

Fig. 2 shows on larger scale a cross-section through the open file.

Fig. 3 is a perspective view of a clamping spring the ends of which form holding means 60 for a filing pin.

Figs. 4, 5 and 6 are different views of the clamping device in the file.

Figs. 7 and 8 show two other forms of construction of the holding means for the filing pins formed by the ends of a clamping spring.

Figs. 9 and 10 are part views of files fitted with the file pin holding means shown in Figs. 7 and 8 respectively.

Fig. 11 shows in cross-section the application of the claw-like holding means shown in Fig. 8.

70

Fig. 12 shows a covering bar used with same.

Fig. 13 is a section on line 13—13 of Fig. 12 75 on larger scale.

Referring to Figs. 1 to 6 clamping springs 2 in the form of flat strips each bent so that its ends are adjacent to each other are inserted in the back of the file 1. One of the two ends of the clamping spring has an extension of reduced width with a slot 3 therein forming an eye, and the other end has a similar extension with an incision 4 forming a hook, so that the filing pins can traverse the eye and the hook.

To file periodicals the right-hand cover of the file is slightly lifted so that the filing pin 5 is separated from the hook 4 and the papers can be filed (position Fig. 6).

90

After the periodicals have been filed on the filing pin 5, this pin can be inserted in the hook 4 and its free end inserted into the open end of the pocket 7 of the cover. The rear end of the filing pin can be fixed in the left cover of the file, or both ends of the pin may be inserted into pockets 7 of the cover as shown in Figs. 11 and 14.

95

The perforations in the first and last sheets, periodicals and the like which have been filed 100

cannot be widened by the filing pins, as the ends of the clamping springs forming the holding means for the filing pins project over the edges of the cover back and form a frame around the perforations.

5 Referring to Fig. 7 the pin-holding means consists of latches 8 in the ends of the clamping spring 2. As shown in Fig. 7 the ends of the clamping springs 2 are bent over so that 10 they form a guide for the latches 8. The latches 8 are arranged longitudinally shiftable and hold the pins 5 tightly in that they grip over their arms (Fig. 9). Fig. 9 shows in top plan view a file 1 fitted with this file-holding means.

15 Figs. 8, 10, and 11 show claws 9 in the ends of the clamping spring, said claws designed to engage with corresponding depressions 10 of bars 11. Each bar 11 as shown in Figs. 20 10, 12 and 13 is of thin flexible material and preferably stuck on a sheet 12. A separate sheet 12 with a thin metal bar is preferably arranged on the inner surface of the corresponding cover in all the different forms of 25 holding means for the filing pins, in order to preserve intact the first and last sheets of the papers filed.

I claim:—

30 1. A file for holding the papers, books and the like to be filed, the pile of filed papers being compressed at the filing points, comprising in combination with the file back, the filing pins and clamping springs inserted in the file back at the leaf-impaling points so

35 that their ends project over the edges of the file back, said ends of said clamping springs constructed to form holding means for said filing pins.

2. A file for holding the papers, books and 40 the like to be filed, the pile of filed papers being compressed at the filing points, comprising in combination with the file back, the filing pins and clamping springs inserted in the file back at the leaf-impaling points so 45 that their ends project over the edges of the file back, said ends of said clamping springs constructed to form holding means for the filing pins, said holding means covering frame-like the perforations in file papers.

50 3. A file for holding the papers, books and the like to be filed, the pile of filed papers being compressed at the filing points, comprising in combination with the file back, the filing pins and clamping springs inserted in the file back at the leaf-impaling points, an 55 extension on each end of each of said clamping springs, projecting over the edges of the file back, one of said extensions having an eye and the other of said extensions having a 60 slot adapted to engage in said eye to form holding means for said filing pins.

4. A file for holding the papers, books and the like to be filed, the pile of filed papers being compressed at the filing points, comprising in combination with the file back, the

70 filing pins and clamping springs inserted in the file back at the leaf-impaling points so that their ends project over the edges of the file back, claws on the ends of said springs adapted to form holding means for said filing pins.

75 5. A file for holding the papers, books and the like to be filed, the pile of filed papers being compressed at the filing points, comprising in combination with the file back, the filing pins and clamping springs inserted in the file back at the leaf-impaling points so that their ends project over the edges of the file back, latches in the ends of said clamping springs adapted to form holding means for 80 said filing pins.

85 6. A file (with filing pins) for holding the papers, books and the like to be filed, the pile of filed papers being compressed at the filing points, comprising in combination filing pins, claw-like clamping springs inserted in the file back at the filing points so that their ends project over the edges of the file back, said ends of said clamping springs constructed to form holding means for said filing pins, separate sheets on the inner surface of the two covers, and a cover bar on each 90 separate sheet having depressions adapted to receive said claw-like holding means.

95 In testimony whereof I affix my signature.

JAKOB BECK.
